United States Patent Office

Des. 227,907
Patented July 24, 1973

227,907

MICROPHONE GRILLE

Andrew Kainass, Syracuse, N.Y., assignor to General
Electric Company, Syracuse, N.Y.

Filed Jan. 14, 1972, Ser. No. 218,041

Term of patent 14 years

Int. Cl. D14—99

U.S. Cl. D26—14 G

FIG.1

FIG.2

FIG.3

FIG. 1 is an isometric view of a microphone grille in accordance with my invention;

FIG. 2 is a side elevation view; and

FIG. 3 is a top plan view.

The broken lines are shown for illustrative purposes only.

I claim:

The ornamental design for a microphone grille, as shown and described.
